COMBINED LAMP SHADE AND SOCKET FOR
ELONGATED TUBULAR LAMPS

Victor I. Zelov, Rosemont, Pa.

Application March 12, 1948, Serial No. 14,582

4 Claims. (Cl. 240—51.11)

1

This invention relates to electrical devices, more particularly to electrical lighting fixtures, and has for an object to provide improved apparatus of this character.

Heretofore, in the design and manufacture of lighting fixtures for use of elongated bulbs or tubes having pairs of contact prongs projecting beyond the ends thereof, for example, fluorescent light bulbs or tubes, it has been customary to provide a multi-part socket of insulating material for reception of the pair of prongs on the tube. Such sockets comprise not only the plurality of parts of insulating material, but also a pair of metallic contact elements, screws for connecting wires to the contact elements, and one or more fastening devices for securing together the several parts of the insulating material forming the socket member, with the contact elements and their associated parts assembled therein. In addition, means must be provided for securing the assembled socket to the shade, reflector, or other structure housing the light bulb or tube.

The present invention provides a simplified substitution for the above-described complicated arrangement, involving a bulb or tube shade or housing of insulating material, with one or more ends of the housing so constructed and shaped as to constitute, in itself, either the entire contact socket, or a portion thereof.

Where the housing defines only a portion of the socket, the invention provides a single member cooperating therewith to complete the socket and to provide the means for connecting wires to the metallic contact members housed in the socket.

Accordingly, another object of the invention is to provide a one-piece combination bulb or tube housing and contact socket.

Yet another object of the invention is to provide a lamp bulb or tube shade or housing having an end wall shaped to cooperate with a partial socket member to define with the latter a complete socket.

Another object of the invention is to provide a lamp shade which functions also as a socket for the lamp or bulb it shades.

A further object of the invention is to provide novel means for connecting wires to their electrical contact elements.

Another object of the invention is means, integral with a combined lamp shade and socket, for supporting and retaining a reflector within the shade.

These and other objects are effected by the 55 end walls 17, all cooperating to partially enclose

2

invention as will be apparent from the following description and claims taken in accordance with the accompanying drawings, forming a part of this application, and in which:

5 Fig. 1 is a top plan view of a bed lamp incorporating novel features of the present invention;

Fig. 2 is a bottom plan view of the bed lamp shown in Fig. 1;

10 Fig. 3 is an enlarged, fragmentary, top plan view of the structure shown in Figs. 1 and 2, with the top or cover portion of the shade removed;

Fig. 4 is a sectional view, taken along the line IV—IV of Fig. 3, looking in the direction indicated by the arrows;

Fig. 5 is a sectional view, taken along the line V—V of Fig. 3, looking in the direction indicated by the arrows;

Fig. 6 is a transverse sectional view, taken 20 along the line VI—VI of Fig. 1, looking in the direction indicated by the arrows;

Fig. 7 is an enlarged top plan view of a key member which serves to retain the wires in engagement with the metallic contact elements;

25 Fig. 8 is an enlarged, fragmentary, bottom plan view of one end of a shade and socket of another form, constructed in accordance with the present invention;

Fig. 9 is a fragmentary sectional view, taken 30 along the line IX—IX of Fig. 8, looking in the direction indicated by the arrows;

Fig. 10 is a transverse sectional view, taken along the line X—X of Fig. 8, looking in the direction indicated by the arrows, the socket being omitted in the interest of clarity;

Fig. 11 is an inner end view of the socket, taken along the line XI—XI of Fig. 8, looking in the direction indicated by the arrows;

Fig. 12 is a fragmentary sectional view, taken 40 along the line XII—XII of Fig. 11, looking in the direction indicated by the arrows; and,

Fig. 13 is an outer end view of the socket, separate from the shade structure.

Referring now to the drawings more in detail, 45 and particularly to Sheet One thereof, the reference character 10 indicates, in its entirety, a fluorescent bed lamp comprising a cover 11 having a pair of arms 12 projecting rearwardly therefrom and terminating in downwardly-extending portions 13, by which the lamp may be supported on the headboard of a bed, or the like, in the usual manner.

Preferably, the cover 11 includes a top wall 14, front and rear walls 15 and 16, respectively, and 50 end walls 17, all cooperating to partially enclose

and conceal a bulb or tube shade or housing 20. This housing 20 comprises a dome 21 having a horizontal flange 22 projecting outwardly in all directions from its lower edge. The front and end portions of the flange 22 are closely received in rabbets 26 in the lower edges of cover front and end walls (Fig. 6). The rear portion of the flange 22 has a flange 23 extending vertically from its edge and abutting the rear wall 16 of the cover 11.

The tube shade or housing 20 and cover 11 may be secured in assembled relation by a pair of screws 27 extending through the end portions of the flanges 22 into bosses 28 on the end walls 17 of the cover (Fig. 2). Bosses 29 at the rear of the tube housing may carry dowels 30 which are received in mating recesses 31 in aligned bosses 32 on the cover rear wall 16 (Fig. 6).

The tube-receiving recess 25, defined by the dome 21, has extensions at its ends providing socket chambers 35 (Figs. 2, 4 and 5). Each socket chamber 35 is defined by side walls 36 and 37, a top wall 38 and an end wall 39. The socket chambers 35 are open at the bottom in a manner similar to the main tube recess 25, and are in unobstructed communication with the latter through their common open ends.

A vertical partition 41, extending downwardly from socket chamber top wall 38, separates the upper portion of the chamber into a pair of compartments 42 and 43 in which are disposed a pair of resilient metallic contact elements 44.

Each contact element 44 includes a toe portion 45 at its upper end, engaged in a recess 46 in the socket chamber top wall 38 adjacent the central partition 41. The lower end 47 of each contact element bears against the adjacent socket side wall 36 or 37. The intermediate portion of each contact element is comprised by a pair of double reverse loops, the lower large-radius loop 48 extending inward towards the central partition 41 and the upper small-radius loop 49 projecting outward from the compartment 42 through an opening 51 at the top of the side wall 36 or 37.

A U-shaped key member 52, of insulating material, is disposed with its legs 53, (which taper in width towards their free ends), extending through the upper loops 49 of the contact elements 44. Due to their tapered construction, these legs 53 exert a wedging action between the outer sides of the socket 35 and the bare terminal portions 54 of electrical wires 55, which terminal portions are disposed in the bends of the upper loops 49 (Figs. 3 and 5). Accordingly, the key members 52 not only serve to anchor the metallic contact elements 44 with respect to the socket 35, but also may provide suitable connections between the contact elements and their wires 54-55, although it is preferred that such connections be effected by spot welding, soldering, etc.

The lower loops 48 may be provided with re-entrant portions 50 for frictional retention of the prongs P of the tube T.

Inasmuch as the cover 11, the tube housing 20, the sockets 35 and the keys 52 are all constructed of insulating material, (for example, thermo-setting plastics), the only metallic parts are the screws 27, the contact elements 44, and the wires 54. Since the shade or tube housing 20 and the sockets 35 are formed in a single piece, as by molding, assembly of the complete structure is extremely simple. Obviously, the cover 11 is not functionally essential to the apparatus; its

main use being to conceal the connections of the wires with the contact elements and to improve the general appearance of the device.

Referring now to Sheet Two of the drawings, in which there is illustrated a modified application of the present invention, the reference character 100 indicates, in its entirety, a fluorescent lamp and shade combination comprising a tube T having the usual pair of contact prongs P projecting axially beyond an end thereof for engagement in a partial contact socket member 101 of insulating material carried by a shade member 102, likewise of insulating material, the latter forming one wall of a contact element chamber 103, formed in the partial contact socket member 101.

The contact element chamber 103 is defined by a circular side wall 104 having a throat opening 105 at the top thereof (Fig. 13). This throat extends vertically through a neck portion 106 comprised by side walls 107 and the neck portion 108 of an end wall 109 cooperating with the neck side walls 107 and the circular side wall 104 of the chamber 103.

The side of the chamber 103 opposite to the wall 109 is normally closed by the end wall 111 of the shade member 102 when the partial socket member 101 is secured thereagainst by the bolt 112 and nut 113 (Figs. 9 and 11). As clearly shown in Fig. 8, the edge of the circular side wall 104 which abuts the end wall 111 of the shade member is curved, as at 114, to conform to the curvature of said end wall.

When the partial socket member 101 is separated from the shade end wall, the interior thereof is exposed, thereby rendering readily accessible the pair of metallic contact elements 116 housed in the chamber 103.

A vertical partition 117 divides the chamber 103 and the throat 105 into a pair of compartments 118 and a pair of passages 119, respectively. The central portion of the partition 117 is enlarged, as at 121, to provide a pair of shoulders 122 limiting inward movement of the prongs engaging portions 123 of the metallic contact elements 116, and a pair of ledges 124 cooperating with notches 126 thereabove in the partition to position the upper terminal portions of the metallic contact elements. The contact elements 116 are further positioned by engagement of their intermediate shoulders 127 with mating recesses 128 in the chamber side wall 104.

Vertical slots 131 are provided through the partial socket member end wall 109 and the bottom portion of the circular side wall 104 for insertion and removal of the tube prongs P into and from engagement with the portions 123 of the contact elements 116.

The pair of passages 119 in the neck 107 of the partial socket member receive wires 132 whose bare terminal portions 133 engage the upper portions of the metallic contact elements and are clamped thereby against the end wall 109 forming a wall of the passages, in a manner to be hereinafter explained.

The inner surface of the shade end wall 111 is provided with a central vertical rib 135 and a pair of side vertical ribs 136 at opposite sides of the central rib 135 and of greater height than the latter. As best shown in Fig. 12, the upper portion of the partition 117 in the neck 108 of the socket member is of greater height than the side walls 107 of the neck, with the result that the pair of side ribs 136 on the shade straddle the partition 117 and bear on the neck side walls

107 and on the edges of the metallic contact elements 116, to urge the latter into clamping engagement with the bare terminal portions 133 of the wires 132. In Fig. 13, one side rib 136 is shown, by dot-dash lines, superimposed in its normal position with respect to the partial socket structure.

The edge of the circular side wall 104 extends beyond the corresponding edges of the neck side walls 107 the change in elevation being defined by shoulders 138 parallel to the outer sides of the pair of vertical ribs 136 (Fig. 13.) When the socket member 101 is assembled on the shade 102, these shoulders 138 abut the outer sides of the ribs 136 to position the partial socket member relative to the shade. The socket member is further positioned by engagement of the lowermost portion 135a of the central rib 135 in a mating notch 140 in the edge of the bottom portion of the circular wall 104 (Figs. 8, 11 and 13).

In Figs. 9 and 11, three projections 150 are shown on the neck portion 108 of the partial socket member end wall 109, these projections 150 functioning to position and retain a reflector member 151, which may be of enameled metal or any suitable material having a light-reflecting surface at the lower or under side.

It will be apparent from the above description that this modification of the invention provides a one-part partial socket member normally closed by abutment against the shade member, and accessible by removal of a single bolt. Also, as in the case of the first-described construction, means are incorporated for making novel electrical connections between the wires and the metallic contact elements without the use of screws, nuts, or the like.

While the invention has been shown in but two forms, it will be apparent to those skilled in the art that it is not so limited, but is susceptible of various changes and modifications, without departing from the spirit thereof.

What is claimed is:

1. In apparatus for supporting an electric light bulb or tube of the type having a pair of contact prongs extending axially beyond an end thereof, a bulb shade of insulating material open at the

bottom and closed at the top, sides and ends by wall structure; a partial double-contact socket comprising a body of insulating material including a pair of opposed side walls, a bottom wall and an end wall with the two last-mentioned walls joining the opposed side walls, and a rib carried by the end wall and disposed intermediate the opposed side walls and defining therewith a pair of spaced grooves; a pair of metallic contact elements disposed one in each groove of said pair of spaced grooves for engagement by a pair of contact prongs on an electric light bulb or tube when the latter is assembled in the shade; a pair of spaced ribs extending inwardly from an end wall of the shade for mating reception in the pair of spaced grooves in the partial socket body; and means for retaining the partial socket body and the bulb shade in the relation specified.

2. Structure as specified in claim 1, wherein the height of the pair of spaced ribs is less than the depth of the mating pair of spaced grooves, whereby space remains between the bottoms of said grooves and the tops of said ribs constituting passages for wires to provide electrical connections with the metallic contact elements.

3. Structure as specified in claim 1, including a third rib extending inwardly from the end wall of the bulb shade below the pair of spaced ribs for mating reception in a groove in the bottom wall of the partial socket body.

4. Structure as specified in claim 1, wherein the bottom and end walls of the partial socket body have a pair of openings therethrough for passage of the electric light bulb or tube contact prongs into engagement with the metallic contact elements within said partial socket body.
